UNITED STATES PATENT OFFICE.

ELIZABETH BRATTON, OF COLUMBUS, OHIO.

DESIGN FOR A TOY BLOCK.

55,587.

Specification for Design.

Patented July 6, 1920.

Application filed December 26, 1919. Serial No. 347,617. Term of patent 14 years.

To all whom it may concern:

Be it known that I, ELIZABETH BRATTON, a citizen of the United States, residing at Columbus, in the county of Franklin and State of Ohio, have invented a new, original, and ornamental Design for Toy Blocks, of which the following is a specification, reference being had to the accompanying drawing, forming part thereof.

Fig. 2 is a perspective view showing the other three sides.

I claim:

The ornamental design for a toy block, as shown.

ELIZABETH BRATTON.
